Primary Examiner — Sheryl Lane(74) *Attorney, Agent, or Firm* — Fitch, Even, Tabin & Flannery, LLP**(57) CLAIM**

We claim the ornamental design for an emitter inlet, as shown and described.

DESCRIPTION

FIG. 1 is a perspective view of an emitter inlet in accordance with our new design;

FIG. 2 is a right side elevation view of the emitter inlet of FIG. 1;

FIG. 3 is a rear elevation view of the emitter inlet of FIGS. 1-2;

FIG. 4 is a left side elevation view of the emitter inlet of FIGS. 1-3; and,

FIG. 5 is a front elevation view of the emitter inlet of FIGS. 1-4.

The broken lines in the drawings represent environment and form no part of the claimed design.

1 Claim, 3 Drawing Sheets# US D826,662 S
